[57] **CLAIM**

The ornamental design for a pitched roof anchor, as shown and described.

DESCRIPTION

FIG. 1 is an environmental perspective view of pitched roof anchor showing my new design;

FIG. 2 is a perspective view showing my design mounted on a roof rafter in phantom outline;

FIG. 3 is a front elevational view, which is the same as the rear elevational view;

FIG. 4 is a right side elevational view, which is the same as the left side elevational view;

FIG. 5 is a top plan view; and,

FIG. 6 is a bottom plan view.

No claim is made to the portions in phantom outline as such is for environmental illustration only.
